(57) **CLAIM**

The ornamental design for a cable management rack, as shown and described.

DESCRIPTION

FIG. 1 is a front perspective of a cable management rack showing our new design;

FIG. 2 is a side elevational view thereof;

FIG. 3 is a front elevational view thereof;

FIG. 4 is a bottom plan view thereof;

FIG. 5 is a top plan view thereof; and,

FIG. 6 is a rear elevational view thereof.

The broken line showing in FIGS. 1-5 is included for the purpose of illustrating environmental structure only and forms no part of the claimed design.
